UNITED STATES PATENT OFFICE.

GEORGE H. STRONG, OF CHICAGO, ILLINOIS, ASSIGNOR TO LAWRENCE W. TATUM, OF CLEVELAND, OHIO.

TOOL-SHARPENER.

SPECIFICATION forming part of Letters Patent No. 277,957, dated May 22, 1883.

Application filed March 19, 1883. (No model.)

To all whom it may concern:

Be it known that I, GEORGE H. STRONG, a citizen of the United States of America, residing at Chicago, in the county of Cook and State of Illinois, have invented certain new and useful Improvements in Tool-Sharpener, of which the following, in connection with the accompanying drawings, is a specification.

In the drawings, Figure 1 is a side view of 10 a tool-sharpener embodying my invention. Fig. 2 is a top view of the same. Fig. 3 is a section in the plane of the line $x-x$, and Fig. 4 is a section in the plane of the line $x'-x'$.

Like letters of reference indicate like parts. 15 A represents the base or standard of a tool-sharpener provided with my improvements. The upper part of this standard is forked, or consists of two branching and upwardly-extending arms, a and a' . The arm a has a removable extension, a'' , with a depending cylindrical stem, a''' , which freely enters a socket in the upper end of the arm a .

B is a set-screw or binder for clamping or holding the stem a''' firmly in place.

20 C is a grindstone, and C' is the grindstone-shaft. The shaft C' has a bearing in the part a'' . The inner end of the grindstone-shaft, which end carries the grindstone, is screw-threaded, and D D are nuts run thereon, and 30 the grindstone is clamped firmly between these nuts, so as to be rotated with its shaft.

E is a pulley wheel or driver on the grindstone-shaft, and E' is a pinion thereon.

35 F is a spur-wheel, provided with a handle, F', and engaging the pinion E'. The wheel E and the spur-gear are not both essential, but may be used interchangeably for rotating the shaft, and when the spur-gear is not used the shaft may be provided with a handle, so that it may be rotated either by hand or by means of the wheel E.

40 G is a horizontal plate on the upper end of the arm a' , and b is a dovetail groove in the upper side or face of the said plate.

45 H is a sliding plate having a dovetail rib or extension, b' , fitting into the groove b, and c c are cross-grooves in the upper side or face of the plate H. The movement of the plate H is limited by means of a stop-pin, d, on each 50 end thereof, which pins strike a central fixed

pin or part; but this movement may be limited in any well-known or suitable way.

I is a sliding plate having on its lower side ribs, which enter the grooves c c; and e is a circular slot in the said plate.

55 J is a plate pivoted at one corner to the plate I. This plate has on it the vertical flanges or shoulders e' e''.

K is a sliding block, having in its forward edge a groove, f.

60 L is a screw turning in a female screw in the shoulder e'', and swiveled at its forward end to the block K.

M is a screw passing freely through the plate I and through the slot e, and N is a nut 65 on the lower end of the said screw.

70 O represents an engraver's tool. To use this sharpener, I place the tool to be sharpened in the groove f, and turn the screw L until the tool is firmly clamped between the block K and the shoulder e'. I then set the plate J until the tool is presented at a proper inclination to the stone, and tighten the screw M. As the plate I may be moved to and from the stone, I am enabled to hold the tool firmly against the 75 stone and withdraw it for inspection; and as the plate H may be moved back and forth in a direction parallel to the stone, the tool may also be moved back and forth on the grinding face or side of the stone while the latter is being rotated. By this means the tool, while being sharpened, will always be held at the same 80 inclination to the stone, and may be set with facility to the proper angle. The tool, while being sharpened, may be held by its handle. 85

80 P is a seat, on which I place a whetstone, the grindstone being first removed by removing the part a'' and the parts mounted thereto altogether. The whetstone may be held in its place by one hand while the tool is moved by 90 the other, and the tool will be retained at the proper angle, as before described.

95 While I have shown an engraver's tool in the drawings, it is obvious that other tools may be sharpened by the means described. The grindstone may be adjusted vertically, and also set at an angle in a horizontal plane by means of the screw B. It may also be removed, and another of different size substituted.

100 Having thus described my invention, what I

claim as new, and desire to secure by Letters Patent, is—

1. The combination, in a tool-sharpener, of the sliding block K and its adjusting-screw, the pivoted plate J, provided with the shoulder e' , and serving, in conjunction with the said block, as a jaw for holding the tool, the screw M and its nut N, and the sliding plate I, having therein the curved slot e , all arranged for operation together substantially as specified, and for the purposes set forth.

2. The combination, in a tool-sharpener, of the grooved sliding block K, the screw L, swivel-jointed to the said block, the pivoted plate J, provided with the shoulder e' , the clamping-screw M and its nut, the sliding plate

I, having therein the curved slot e , and the sliding plate H, substantially as and for the purposes specified.

3. The combination, in a tool-sharpener, of the stone C and its shaft, the sliding block K and its adjusting-screw, the pivoted plate J, the screw M and its nut N, the sliding plates H and I, the latter having therein the curved slot e , and the two-armed standard A, with its removable bearing a'' , substantially as and for the purposes specified.

GEORGE H. STRONG.
